UNITED STATES PATENT OFFICE.

RICHARD R. SCOGGAN, OF JEFFERSONVILLE, INDIANA, ASSIGNOR TO KENTUCKY SWITCH & SIGNAL CO., INC., OF ST. MATTHEWS, KENTUCKY, A CORPORATION OF KENTUCKY.

AUTOMATIC ELECTRICALLY-CONTROLLED TRACK-SWITCH.

1,395,872.

Specification of Letters Patent. Patented Nov. 1, 1921.

Application filed August 4, 1920. Serial No. 401,152.

To all whom it may concern:

Be it known that I, RICHARD R. SCOGGAN, a citizen of the United States, residing at Jeffersonville, in the county of Clark and State of Indiana, have invented new and useful Improvements in Automatic Electrically-Controlled Track-Switches, of which the following is a specification.

This invention relates to electrically controlled railway switches and affords improvements in the operation and construction of switches of this general type.

An object of the invention is to provide a trolley wire contactor of greatly reduced weight, size, length and number of parts, and which reduces arcing to a minimum and requires no deflection of the trolley wire, but eliminates the arc barrier, and the necessity of trolley contact runways of unequal length. My invention also furnishes a circuit changer or relay which maintains the current to the ground magnets for an adjustable and uniform length of time, regardless of the car speed and length of trolley contactor.

Another object of the invention is to provide a locking device which requires no extra or special contact plate or runway on the trolley contactor and no extra wire leading from the trolley contactor to the locking device. A time element is also provided which is simpler than those now in general use and not influenced by temperature changes as are dash pots which are frequently used in electrically controlled switches. Furthermore a time governed movement is initiated by contact of the trolley wheel with the contactor runways and operates to open a circuit to the ground magnets either before or after the trolley wheel passes from under the trolley contactor.

Another object of this invention is to furnish means for continuing the current to the ground magnets for a definite time interval and then automatically cutting it out, in order that a retarding means or dash-pot may be used if desired, for retarding the tongue movement of the switch in order to prevent the splashing of pedestrians in wet weather.

Other objects of the invention including novel features of construction and mode of operation will become apparent on reference to the following specification, which de-

scribes the invention in connection with the accompanying drawings.

In the drawings:

Figure 1 is a plan view somewhat diagrammatic of the relay or circuit changer used in connection with my improved mechanism.

Fig. 2 is a view similar to Fig. 1 showing a circuit breaker associated with the time controlling element in open position and the resulting arrangement of circuits.

Fig. 3 is a side elevation partly in section of the novel construction of trolley wire contactor or trolley pan and the means for supporting the same.

Fig. 4 is an end view of the contactor shown in Fig. 3 the trolley wire being shown in section.

Fig. 5 is a sectional view on the line 5—5 of Fig. 3.

Fig. 6 is a sectional view on the line 6—6 of Fig. 3, looking in the direction of the arrows.

Referring more particularly to Figs. 1 and 2 the numeral 10 designates a frame preferably of cast iron adapted to be secured to a base of wood or other insulating material and inclosed in a housing preferably mounted on a pole at the curb adjacent the switch. The frame 10 forms the cores of three separate magnetic windings herein designated as 11, 12 and 13. The frame also forms a support for the armatures 14, 15 and 16 respectively associated with each of said magnets.

A plurality of pins 17, 18, 19 and 20 project upwardly from the frame 10 and on these pins are loosely mounted suitable collars 21, 22, 23 and 24 of insulating material, which collars serve to insulate armatures 14, 15 and 16, a rotatable arm 25 and a disk 26, from the pins and the frame 10, the arm 25 and disk 26 being mounted on the pin 19 as shown in Figs. 1 and 2.

Eye-bolts 27 and 28 are screw-threaded into a projection 29 of said frame and locked in adjusted position by means of a set screw 30. Adjustable tension springs 31, 32 are connected respectively at one end to the armatures 14 and 15 through the insulating blocks 33, 34 and at the other end to the eye-bolts 27, 28 respectively. The armatures 14 and 15 are provided with bent portions 35, 36 which are adapted to engage the collars 21 and 22.

respectively in order that said armatures may be moved pivotally about said pins 17 and 18. The other end of the armature 14 is formed with a renewable metallic contact 5 plug 37 adapted to engage alternately carbon contacts 38, 39 in order to shift the controlling circuit from one ground magnet or solenoid to the other.

A leaf or ribbon spring 40 of non-magnetic material such as bronze is riveted at one end 10 as at 41 to the armature 15 adjacent its bent portion 36, extends the length of the armature 15 and is then bent at substantially right angles and the other end of this spring is 15 insulatably connected to a chain 42 the purpose of which will hereinafter appear. The normal position of the spring 40 is against armature 15 throughout the length of the latter, as shown in full lines in Fig. 1, but 20 the armature 15 moves quickly under the influence of the magnet 12 to the position shown in dotted lines in said figure, while spring 40 must move a time-controlling element and therefore is retarded in following 25 this movement of the armature.

An arcuate flange or hub 43 is formed integral or otherwise secured to the disk 26 and chain 42, in normal position, is wound upon said hub and fastened to it at one end. 30 The disk 26 as above described is mounted on the pin 19 extending upwardly from the frame 10 and is insulated therefrom. The arm 25 is also mounted on this pin 19 and insulated therefrom and also from the disk 35 26. The free end of the arm 25 forms a receptacle for a carbon contact 44 adapted to contact with a corresponding contact 45 held in a suitable holder 46 secured to and insulated from the frame 10. The free end 40 of the swinging arm 25 is also formed with a shoulder 47 adapted to be engaged by the free end of the armature 16 which is bent over to more effectively engage the same and thereby provide a positive means for holding arm 25 and its carbon contact 44 away 45 from the contact 45, until the armature 16 is lifted by its magnet 13, when lever 25 again drops and restores contact between carbon elements 44 and 45. The disk 26 is 50 provided with an elongated slot 48 which is adapted to receive at different points throughout its length an adjustable stud bolt 49, the latter being adapted to contact with the arm 25 after a certain amount of rotation of the disk in order that the arm 25 may be moved with the disk and spring 40 after the lost motion has been taken up. It will be evident that by varying the position of the bolt 49 in the slot 48 the time interval 55 required for its engagement with the lever 25 may be accordingly varied. Stud bolt 49 also serves as a counter-weight to restore the disk 26 to its normal position shown in Fig. 60 1 from the position illustrated in Fig. 2. A contact spring 50 is mounted on a strip of

insulating material 51 suitably secured to the base 10 by means of a screw 52. The free end of the spring 50 is located in the path of the armature 15 and makes electrical contact only when said armature is near the magnet 12 as shown in dotted lines in Fig. 1. 70

The armature 14 normally stands against the contact 39 and is only moved into engagement with contact 38 when the current equals or exceeds a certain amount, such as 75 25 amperes, this amount being necessary to sufficiently energize the magnet 11, which is coarsely wound, to attract its armature. The adjustment of the tension on armature 14 is obtained by means of the eye bolt 27. 80

Figs. 1 and 2 also show diagrammatic views of the two trolley contactors or trolley pans, which are preferably identical in construction. The first contactor located on the trolley wire in advance of the switch point 85 is the one used to operate the switch tongue and the second or safety contactor is used to release the armature 16 from shoulder 47 which permits the contact 44 to resume its normal position in engagement with the contact 45 so that the following car may move the tongue of the switch. At the bottom of Figs. 1 and 2, a diagrammatic view is shown of an electric track switch having two operating solenoids 87, 89 one to throw the 90 switch tongue in one direction and the other to return it. 95

In Figs. 3 to 6 a trolley wire contactor and the means for supporting the same and the trolley wire are illustrated. Numerals 60 and 60^a represent end brackets having a channel for receiving the trolley wire 61 and also a V-shaped section, the sides of which, designated as 62 in Fig. 5 receive the sides of a rectangular insulating block 63. The numerals 64 and 64^a designate angle strips of metal which are bolted to the block 63 by means of the bolts 65, 65^a which penetrate through opposite sides of the block. The angles 64, 64^a thus form a beveled channel 100 or runway for the trolley wheel 66 and are insulated from the trolley wire and from each other and may be or may not be of equal length. The numerals 67, 67^a designate trolley wire ears which have a curved or grooved lower edge adapted to hold the trolley wire firmly down in the channel of the brackets 60, 60^a. The members 67, 67^a are T-shaped at one end (see Fig. 4) the extending arms of the T-section being secured 105 to the brackets 60, 60^a by means of fastening devices 59, 59^a. A casting 69 is bolted to the upper face of the block 63 preferably by the extended bolt 65^a and this casting is provided with a boss 70 adapted to receive the 110 threaded stem of a standard trolley wire insulated hanger 71 which forms a support for the whole contactor. 115

If a motorman approaching a switch of the type above described desires to take the 120

straight or main track he should shut the power off and allow his car to coast. When the trolley wheel meets the trolley contactor runways 64, 64^a it connects them electrically and a current of about one-quarter ampere, for instance, flows from the trolley wire over a wire 75 through magnet 11 (but does not operate its armature) wire 76, angle iron 64^a, across the trolley wheel to angle iron 64 through a wire 76^a connected to the latter, magnet 12, wire 77, across contacts 44, 45, through wire 78 which leads through a resistance 79 to ground. This one-quarter ampere current is however sufficient to actuate the armature 15 by energizing the magnet 12 which consequently quickly draws the armature away from the spring 40 to the position shown in dotted lines in Fig. 1. The spring 40 being now under tension, 20 swings over until it touches armature 15 and while so moving it rotates the disk 26 by pulling on the chain 42 until the stud 49 strikes against arm 25 and raises it until the armature latch 16 drops behind the 25 shoulder 47 and thus maintains the contacts 44 and 45 in separated position.

The free end of the armature 15 is provided with a socket holder 80 adapted to receive a contact 81 which cooperates with 30 a contact 82 carried in a suitable holder 83 attached to the supporting base of wood or other suitable insulating material. When the magnet 12 is energized and the armature 15 is instantly attracted, the contacts 81 35 and 82 are closed which allows a current of eight amperes (for instance) to flow immediately through wire 75, magnet 11, wire 76, wire 84 which contacts with armature 15, through the latter to contacts 81 and 82 40 through a conductor 85 to the armature 14, and from the latter to contact 39 (armature 14 being against contact 39 because a current under twenty-five amperes is not sufficient to actuate it) then through a wire 45 86 to solenoid 87 and then to ground. This action takes place while the arm 25 is being raised but as soon as stud 49 contacts with and moves contact 44, the magnet 12 is de-energized and the armature 15 recedes carrying contact 81 away from contact 82 and thus breaking the circuit to the solenoid 87. This time interval should be ample to maintain a current through solenoid 87 or 89 long enough to allow the heavy track- 55 switch tongue to move from one position to the opposite one. This time interval is entirely separate and independent of the time required for the trolley-wheel to pass under the trolley contactor.

60. A motorman desiring to turn off the main track does not shut off the power but draws a heavy current of about 25 amperes, for example, from the trolley wire through wire 75, magnet 11 (this current being sufficient 65 to operate the armature of said magnet),

wire 76, angle iron 64^a and through the car to ground. This current of 25 amperes or more passes through the large wires 75, 76, through the car to ground and serves only to shift the armature 14 from contact 39 to 70 contact 38. A current of about one-quarter ampere crosses by means of the trolley wheel from angle iron 64^a to angle iron 64 energizes magnet 12, closes contacts 80, 82 and allows current to pass over the same 75 path as described in the preceding paragraph, where the track-switch was thrown for the main track, until it reaches the armature 14. From there the current flows through contact 38, wire 88 and solenoid 89 80 to ground. The solenoid 89 is used to operate the switch in opposite direction from the solenoid 87. It will be noted that in throwing the contact switch in either direction, the same path is followed by the actuating 85 current until it passes out of the armature 14 when it goes through either contact 39 or 38. Whenever a trolley wheel passes under a trolley wire contactor, magnet 12 closes the contacts 81, 82 and holds them closed 90 until the rotating disk and pin 49 opens the circuit between the contacts 44 and 45, whereupon magnet 12 is deenergized and armature 15 swings outward and breaks the circuit to the solenoids by separating the 95 contacts 81 and 82. This action provides for the continuation of the current to the solenoids for a certain length of time regardless of the time that the trolley wheel is on the trolley contactor. This makes it 100 possible to use a very short and consequently a very light trolley contactor.

The contact spring 50 is adapted to engage the armature 15 when the latter is attracted by magnet 12 and receives a current from it 105 with which to energize the magnet 12 through the connection 90 so that if the trolley wheel happens to leave the trolley contactor before the contacts 44 and 45 have been separated the switch will nevertheless 110 be thrown in the manner above described. When arm 25 is raised the armature 16 drops and engages shoulder 47 so as to hold it in raised position, thereby rendering the magnet 12 inoperative until the car advances to 115 the second trolley contactor placed beyond the switch. When the trolley wheel spans the two runways of the second contactor the current flows from the angle iron 91, through the trolley wheel to angle iron 91^a, through 120 wire 92 to magnet 13, and through wire 93 and resistance 79 to ground, thus energizing magnet 13 and disengaging armature 16 from the shoulder 47, releasing arm 25 and restoring the contact between 44 and 45 125 which establishes the connections in normal position so that a following car may operate to throw the switch after the first car has reached the second trolley contactor. The second trolley contactor is placed far enough 130

from the first one to allow the first car to reach a safety point before the circuit is again closed between contacts 44 and 45.

It is believed that the many advantages 5 of the electrically controlled railway-switch constructed in accordance with the foregoing description may be readily understood, and it may furthermore be stated that changes, variations, and modifications can be resorted 10 to without departing from the spirit of the invention or sacrificing its advantages and I therefore do not wish to restrict myself to the details of construction as shown in the accompanying drawings and described in the 15 specification forming a part of this application; but reserve the exclusive right to make such changes, variations and modifications as come properly within the scope of the appended claims.

20 Having thus fully described my invention, what I claim as new and desire to secure by Letters Patent, is:—

1. In a switch operating mechanism, the 25 combination of a double solenoid for throwing the switch, an electro-magnet adapted to control a circuit leading to one or the other of said solenoids and a second electro-magnet having an armature working between two fixed contacts adapted to place one or the 30 other of said solenoids in the circuit according as the car entering the switch applies or does not apply power to the motors thereof.

2. In a switch operating mechanism, the 35 combination of contactors adapted to be electrically connected by the trolley wheel, an electro-magnet having its winding included in a circuit with the contactors and trolley wheel, a circuit breaker in said circuit normally in operative position for closing the 40 circuit and requiring a uniform time to break the circuit after the initial closing thereof by the trolley wheel and means for maintaining the circuit during the time required for said breaker to function irrespec- 45 tive of the position of the trolley wheel.

3. In a railway switch operating mechanism, the combination of an electrically operated switch throwing device, means for maintaining 50 the electrical circuit to said switch throwing device for a uniform length of time and then breaking the same, and mechanism for maintaining said circuit broken until the car has passed over a desired distance.

55 4. In a switch operating mechanism, the combination of contactors adapted to be electrically connected by the trolley wheel, an electrically operated switch throwing device, an electrical circuit including said device, a second circuit including the trolley wheel and controlling the first circuit, a circuit breaker in said second circuit adapted to function in a definite time interval after the initial closing of the circuit by said trolley 60 wheel, a latch for maintaining the circuit

breaker in open position and means comprising runways spaced from the contactors, an electro magnet, and a circuit adapted to be closed by the trolley wheel contacting with said runways for energizing said magnet and attracting said latch, thereby releasing the circuit breaker. 70

5. In a railway switch operating mechanism, a circuit closer including an electro-magnet having its winding normally in circuit with contactors electrically connected by the trolley wheel, an armature adapted to be attracted by said magnet, a spring of non-magnetic material connected to said armature tending to follow the movement of the 80 same, and means for delaying the movement of the spring in response to the previous movement of said armature.

6. In a railway switch operating mechanism, the combination of a circuit closer including an electro-magnet having its winding normally in circuit with contactors electrically connected by the trolley wheel, an armature adapted to be attracted by said magnet, means associated with said armature constrained to move in response to the movement thereof, mechanism for delaying the movement of said means including a circuit breaker having a movable part operatively connected to said means and a contact arm 90 adapted to be operated by said part after the latter has been moved a certain distance. 95

7. In a railway switch operating mechanism, the combination of contactors adapted to be electrically connected by the trolley wheel, a circuit including the trolley wheel and an electro-magnet having an armature associated therewith, a spring coöperating with said armature tending to follow the movement of the armature, a circuit breaker in said circuit having a member connected to said spring and a contact arm having a lost motion connection with said member whereby said member is actuated by said spring to take up the lost motion and actuate said arm to break the circuit. 100 105 110

8. In a switch operating mechanism, the combination of a double solenoid for throwing the switch, an electro-magnet having an armature adapted to control a circuit leading to one or the other of said solenoids, a circuit breaker included in circuit with the winding of said magnet adapted to function in a definite time interval after the closing of the circuit controlled by said armature, and a second electro-magnet adapted to place one or the other of said solenoids in the circuit accordingly as the car entering the switch applies or does not apply power to the motors thereof. 115 120 125

9. In a switch operating mechanism, the combination of contactors adapted to be electrically connected by the trolley wheel, one of said contactors being electrically connected to the trolley wire, an electro-magnet 130

- having its winding included in a circuit with said contactors and trolley wheel, means operated by said electro-magnet for closing a shunt from the trolley wire around said 5 contactors, and a circuit breaker in said circuit requiring a uniform time to function after the initial closing of said circuit by the trolley wheel.
10. In a switch operating mechanism, the combination of contactors adapted to be electrically connected by the trolley wheel, one of said contactors being electrically connected to the trolley wire, a circuit breaker, an electro-magnet having its winding included in a circuit with said contactors, trolley wheel, and circuit breaker, means operated by said electro-magnet for closing a shunt from the trolley wire around said contactors for maintaining the current in said 20 winding and through said circuit breaker irrespective of the position of the trolley wheel, said circuit breaker requiring a uniform time to function after the initial closing of said circuit by the trolley wheel.
- 25 11. In a switch operating mechanism, the combination of contactors adapted to be electrically connected by the trolley wheel, one of said contactors being electrically connected to the trolley wire, a double solenoid 30 for throwing the switch, a circuit breaker, an electro-magnet having its winding included in a circuit with said contactors, trolley wheel, and circuit breaker, and means operated by said electro-magnet for closing 35 both a shunt from the trolley wire around said contactors and a circuit leading to one or the other of said solenoids, said circuit

breaker requiring a uniform time to operate after the initial closing of the first named circuit by the trolley wheel. 40

12. In a switch operating mechanism, the combination of contactors adapted to be electrically connected by the trolley wheel, one of said contactors being electrically connected to the trolley wire, an electrically operated switch throwing device, and means for maintaining the operating current to said switch throwing device for a uniform length of time after the initial connection of said contactors by the trolley wheel, regardless of the car speed and lengths of the trolley contactors. 45

13. In a switch operating mechanism, the combination of two trolley contact strips adapted to be electrically connected by the 55 trolley wheel, two track-switch operating solenoids, a circuit for energizing one or the other of said solenoids, said circuit initially including said contact strips and trolley wheel, a controlling magnet in said circuit 60 adapted to shunt a strong current from the trolley wire around said trolley contact strips to the selected solenoid, said shunt being adapted to maintain the energization of said magnet irrespective of the position 65 of the trolley wheel relatively to said contact strips.

In testimony whereof I have hereunto set my hand in presence of two subscribing witnesses.

RICHARD R. SCOGGAN.
